FORM FOR CONCRETE CONSTRUCTION

William E. Borton, Omaha, Nebr.

Application November 20, 1947, Serial No. 787,184

3 Claims. (Cl. 25—131)

1

This invention relates to concrete wall constructions and more particularly it is an object of the invention to provide a form for the casting of such walls.

In the past, the most common way to cast concrete walls and the like has been to build forms of lumber, the latter being torn down after each wall is completed. Considerable waste and expense has been occasioned by this method since, although the lumber can then be reused, it is usually cut to certain sizes and must be re-cut for later work.

A further disadvantage has been in the length of time required to remove nails. Also, the labor cost of assembling such forms has been expensive because of the time required.

It is therefore an object of this invention to provide a form for constructing walls of concrete and the like which may be rapidly assembled.

Another object of the invention is to provide a form of this type, the various parts of which are prefabricated, so that no cutting is required.

Another object of the invention is to provide a concrete form construction which is stronger and more rigid than heretofore.

A further object of the invention is to provide a concrete form the various parts of which are held together without the use of nails and in a manner whereby those parts of the forms which are disposed on opposite sides of a section of a finished wall are accurately spaced apart a selected uniform distance.

Still a further object of the invention is to provide a concrete wall construction which may be re-used without changing the dimensions of the several parts thereof.

Yet another object of the invention is to provide a wall form construction the various parts of which may be economically manufactured.

Other and still further objects and advantages of the invention will become apparent from the following detailed description of a preferred embodiment thereof.

In the drawings:

Figure 1 is a perspective view of a broken-away section of a concrete form of this invention showing its different parts;

Figure 2 is a side elevation of one of the bolts and spacer-sleeves employed, a portion of the spacer-sleeve being broken away; and

Figure 3 is a top plan view of a broken-away end portion of one of the area-covering horizontally disposed wall form members employed.

The form of this invention is for the construction of walls of concrete and the like and is best

2

illustrated in Figure 1 in which may be seen a plurality of types of upright standards each having a different construction, and each being employed in a different portion of the new form. A first group of the upright standards are two-wall corner sets and one of the latter is illustrated at 10.

Each of the sets 10 include two, preferably equi-distantly spaced apart, elongated members 12 and 14. Each of the members 12 and 14 are provided with two longitudinal front surfaces 16 and 18, and 20 and 22. The surfaces 16 and 18 of the member 12 are disposed at an "inside" right-angle with respect to each other; the surfaces 20 and 22 of the member 14 are disposed at an "outside" right angle with respect to each other.

Each of the surfaces 20 and 22 are disposed confronting and in parallelism with one of the surfaces of the other of the members 12 or 14. Thus, the surface 16 of the member 12 is disposed confronting the parallel with the surface 20 of the member 14; similarly the surface 18 of the member 12 is disposed confronting and in parallelism with the surface 22 of the member 14.

Each of the said surfaces are provided with flanges on their longitudinal terminal edges, each of the flanges being disposed at a right angle away from the parallel confronting surface of the other of said members. Thus, the flanges 24 and 26 of the member 12 are disposed at a right angle away from the surfaces 20 and 22 respectively of the member 14; and the flanges 28 and 30 of the member 14 are disposed at a right-angle away from the surfaces 16 and 18 respectively of the member 12.

The purpose of standards of the type 10 is to interconnect two walls where they intersect at a right-angle.

A second group of the standards are one-wall supporting sets, one of which is illustrated in Figure 1 and generally indicated at 40. The one-wall supporting set 40 includes two, preferably equi-distantly spaced apart, elongated members 42 and 44. Each of the members 42 and 44 is provided with a longitudinal surface 46 and 48 respectively, the latter being disposed confronting and in parallelism with each other.

The surfaces 46 and 48 are each provided with and connected with two flanges 50 and 52, and 54 and 56, respectively. The flanges 50 and 52 of the member 42 are disposed at a right-angle away from the confronting surface 48 of the other member 44; similarly, the flanges 54 and 56 of the member 44 are disposed at a right-

3

angle away from the confronting surface 46 of the other member 42. The flanges 50 and 52 and 54 and 56 are all disposed in parallelism with each other, all longitudinal edges of the members 42 and 44 being vertically disposed in use.

The purpose of the one-wall supporting set 40 is for inter-connecting later described wall form members in a straight wall space.

A third group of upright standards are three-wall corner sets for interconnecting later described wall-form members at the intersection between an inner wall and an outer wall or at the point of junction of the terminal end of any wall with a continuous wall. For the purpose of designating this set a three-wall corner set, each wall section which terminates at the three-wall corner upright standard set will be referred to as a wall, even though two of such sections may be in alignment and be for the purpose of forming a continuous wall themselves.

One of the three-wall corner sets is generally indicated at 60, one of the three members of the set 60 being designated by the numeral 62. The member 62 has two parallel, spaced apart flanges 64 and 66 interconnected by a center section 68 having a flat surface disposed at a right-angle to and on the opposite side of the center section 68 from the flanges 64 and 66. The other two members of the three-wall corner set 60 are shown at 70 and 72, and each is provided with a first flat surface 74 and 76 respectively, each disposed in parallelism with the flat center surface 68 of the member 62.

The members 70 and 72 are further each provided with a second surface 78 and 80, each disposed at a right-angle to the surface 68, the surfaces 78 and 80 being disposed in confronting parallelism with each other, and preferably equidistantly spaced from each other. The surfaces 74, 76, 78 and 80 are each provided with a flange 82 on each of their longitudinal terminal edges.

The flanges 82 are each disposed at a right angle away from their adjoining surfaces and are disposed in directions away from those surfaces of the other members of the third set 60, which surfaces are parallel with and confronting those surfaces connected to and adjoining each flange 82.

A fourth group of the upright standards are termed four-wall corner sets and are employed wherever four-wall sections meet in a building or other construction. One of such four-wall corner-sets is generally indicated at 90 in Figure 1 and includes four members 92, 94, 96 and 98, each of which is provided with two surfaces 100 and 102. The surfaces 100 and 102 of different ones of said members are disposed in parallelism with and confronting each other.

Each of the surfaces 100 and 102 are provided with a flange 110 on its longitudinal terminal edge. Each of the flanges 110 is disposed at a right-angle away from its adjoining surface 100 or 102 and away from that surface 100 or 102 of another of the four members 92, 94, 96, and 98, which latter surface confronts the said adjoining surface to which the flange is attached.

A fifth group of the upright standards will be referred to as wall end standards and one of the latter is generally indicated at 120 in Figure 1. The wall end standards are preferably composed of only one member as shown. That member 120 is provided with two longitudinal edges or

4

flanges 122 and 124 projecting outwardly therefrom in opposite directions. The flanges 122 and 124 are preferably disposed in alignment and are inter-connected by means of a U-shaped main body portion 126.

A plurality of normally horizontally disposed area covering, elongated wall form members 150 are provided. Each of the latter is provided with a substantially flat, preferably rectangular web or side surface 152, forming the center section of the member 150. Each member 150 is further provided with two parallel side flanges 154, each disposed at right angles with respect to its adjoining web 152. The flanges 154 are disposed on the longitudinal edges of the members 150.

The wall-form members 150 are each provided with U-shaped, preferably integral, ends 156 on the transverse edges thereof as best shown in Figure 3.

The ends 156 of each member 150 are provided with elongated recesses or slots 158 opening toward the surface 152 of that member. The slots 158 are disposed transversely of the members 150 and at right-angles to the flanges 154.

The oppositely disposed walls 160 and 162 of each slot 158 are parallel and are spaced apart sufficiently for snugly receiving the projecting flanges of the various upright standards 10, 40, 60, 90 or 120. All slots 158 and the flanges of said upright standards are preferably of uniform size.

The U-shaped ends 156, the flanges 154 and the surfaces 152 of each member 150 are preferably all formed by bending and cutting operations from one integral piece of metal.

35 The wall-form members 150 are each provided with two or more, and preferably four, like apertures 170 adjacent the ends thereof.

The members 150 are designed to be placed on either side of a pair of adjacent standards for cooperation with each other. Each aperture 170 of each wall-form member 150 is arranged for disposal in alignment with an aperture in the opposite wall-form member 150.

36 The aligned apertures 170 are for the purpose of receiving one of a plurality of bolts 172. As shown in Figure 2, the bolts 172 are provided with heads 174 and threadedly attached nuts 176.

Each of the nuts 176 are preferably welded to the adjacent wall-form member 150 around their corresponding apertures. This is for the reason that at times when the walls to be formed are below ground, or backed up against other walls, access to those nuts 176 which are on the outer side of the wall to be constructed are inaccessible to the operator during inserting and removing the bolts 172.

If desired, the walls of certain of the apertures 170 may be threaded and the nuts 176 eliminated.

Upon each bolt 172 a spacing sleeve or annular 60 spacing member 178 is attached, the latter being preferably of uniform length and of lengths corresponding to a desired concrete wall width. The sleeves 178 are of larger inner diameter than the diameter of said bolts and larger than the diameter of said apertures.

A plurality of like bolts 172 are disposed through the several upright members forming each one of the sets of standards. The bolts and apertures of the standards are spaced apart sufficiently for purposes of strength. The standards are composed of two or more rigid upright members, the apertures in the several members of a standard, for receiving the bolts 172, are disposed in alignment with each other similarly to the apertures

70 in the wall form members 150.

In operation, the members forming the standards are bolted together, placed upright, and maintained in a desired position while the wall form members 150 are placed in cooperating pairs on either side of each two adjacent ones of the standards, the slots 158 receiving the flanges of the standards and the surfaces 152 of the wall-form members being disposed in confronting, spaced apart, parallelism. The bolts 172 with the spacers thereon are then inserted in aligned ones of the apertures and tightened so that the standards are held together and the wall form members are locked upon the standards holding themselves and the latter standards into a rigid structure. The spacers 178 for the standards and for the wall-form members are preferably of the same size.

The other wall-form members 150 may then be placed in tiers successively disposed one upon the other until the spaces between the wall-form members and between the several parts of the upright members will form a continuous void or space in the shape of the walls of the building. The concrete, indicated at 200 in Figure 1, may then be poured into the said space or void and allowed to harden.

The bolts 172 may then be loosened and removed from the new concrete wall, permitting the removal of the wall-form members and the several sections or members of the standards 10, 40, 60, 90 and 100.

A concrete wall will be left standing, the sleeves 178 being left embedded therein. The standards and wall-form members may then be re-used again in a similar manner.

It will be seen that a wall thus formed may be easily strengthened by placing re-enforcing rods between the wall-form members 150 and between the several members of each standard prior to the hardening of the cement, so that the re-enforcing rods will form a permanent part of the concrete.

The same sizes of standard members can be used for members 42, 44 and 62 and for members 14, 70, 72, 92, 94, 96 and 98, thus cutting initial costs of the forms. Similarly the wall-form members can be standardized into but a few lengths.

It will be further seen that a wall can be built in several portions by using the same set of wall-form members, and even the same set of standards, for subsequent upper portions as for a first horizontal portion of, for instance, the first four feet.

Thus, to construct a twelve foot wall, for example, the latter would be built, using one-third the forms, by employing a single four foot high wall portion three times.

From the foregoing description, it is thought to be obvious that a form for concrete construction in accordance with my invention is particularly well-adapted for use by reason of the convenience and facility with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice, except as claimed.

I claim:

1. A device for the purpose described comprising a plurality of upright standards; a first group of said standards being two-wall corner sets, said two-wall corner sets each comprising two spaced

apart elongated members, each of said members having two longitudinal surfaces disposed at a right-angle with respect to each other, the surfaces of one of said members each being disposed confronting and in parallelism with one of the surfaces of the other of said members, said surfaces each having flanges on their longitudinal terminal edges, the flanges of each of said surfaces being disposed at a right-angle away from the parallel confronting surface of the other of said members; a second group of said standards being one-wall supporting sets, said one-wall supporting sets each comprising two spaced apart elongated members, each of said one-wall set members having a longitudinal surface disposed confronting and in parallelism with a surface of the other, said surface having flanges on their longitudinal terminal edges, the flanges of each of said members being disposed at a right-angle away from the said confronting surface of the other of said members; a third group of said standards being three-wall corner sets, one member of said third group having two parallel flanges interconnected by a center section having a flat surface disposed at a right-angle to and on the opposite side of the center section from said flanges, the other two members of said third group each having a first surface disposed in parallelism with the flat surface of said center section, a second surface disposed at a right-angle to said flat surface of said center section and confronting and parallel to the second surface of the other of said other two members, and the first and second surfaces of said other two members each having a flange on each of its longitudinal terminal edges, said flanges each being disposed away from their adjoining surfaces at a right-angle thereto and in directions away from those surfaces of the other members of said third set which surfaces are parallel to and confronting their adjoining surfaces; a fourth group of said standards being four-wall corner sets, said four-wall corner sets each comprising four members each having two surfaces disposed at a right-angle to each other and each disposed in parallelism with and confronting one of the said surfaces of one of the other members of said four-wall corner set, each of said surfaces of said four members having a flange on its longitudinal terminal edge, each of said flanges being disposed at a right-angle away from its said adjoining surface and away from that surface of another of said four members which confronts said adjoining surface; a fifth group of said standards being wall-end standards, said wall-end standards each having two longitudinal edges projecting outwardly therefrom in opposite directions; a plurality of elongated wall-form members for disposal between said standards, said wall-form members each having a substantially flat side, said wall-form members being provided with U-shaped ends having transverse slots therein disposed at a right-angle to said flat sides and opening toward said flat sides, said slots being of widths for receiving said flanged edges of said standards; and means for securing said wall-form members and said standards together.

2. A device as described in claim 1 in which said wall-form members are disposed in cooperating pairs on opposite sides of and engaging two adjacent ones of said standards; in which said wall-form members are each provided with at least one aperture in alignment with an aperture in the other opposite one of said wall-form members; in which a plurality of bolts are provided,

each bolt being disposed through two of said aligned apertures; and in which spacing sleeves of larger outer diameter than the diameters of said apertures are disposed on said bolts.

3. In a form for the purpose described, a construction for forming a corner between two walls disposed at a right angle to each other comprising: a pair of upright members forming a two-wall corner standard set in use, said uprights being elongated and spaced apart from each other in use, each of said members having two longitudinal surfaces disposed in use at a right angle with respect to each other, the surfaces of one of said members each being disposed in use confronting and in parallelism with one of the surfaces of the other of said members, said surfaces each having flanges on their longitudinal terminal edges, the flanges of each of said surfaces being disposed in use at a right angle away from the parallel confronting surface of the other of said members; a plurality of elongated wall-form members for disposal between different standards sets, said wall-formed members each having a substantially flat side, said wall-form

members having ends having transverse slots therein disposed at a right angle to said flat sides and opening toward said flat sides, said slots being of widths for receiving said flanged edges of said standards; means for securing said uprights together in spaced apart relationship with respect to each other; and means for securing certain of said wall-form members together in spaced apart relationship with respect to each other and to 10 said uprights.
